COMBINATION AND KEY CONTROLLED
LOCK

Frederick M. Mace, San Diego, Calif.

Application January 12, 1953, Serial No. 330,701

3 Claims. (Cl. 70—284)

1

This invention relates to improvements in combination locks operable into closed and open positions by manual rotation of certain elements of the lock in cooperation with the insertion of a key for manipulating and aligning certain other elements of the lock.

Another object is the provision of a lock of this character which may be readily adaptable to other locks employing a locking bolt for actuating the same.

A still further object is the provision of finger-contacting elements arranged circumferentially around the front or key-receiving end of the lock to enable an operator to quickly and conveniently count, by the sense of touch the predetermined necessary revolutions required to operate the combination of the lock.

These and other objects will appear as my invention is more fully hereinafter described in the following specification, illustrated in the accompanying drawings and finally pointed out in the appended claims.

In the drawings:

Figure 1 is a side view of the invention with fragments broken away for convenience of illustration.

Figure 2 is a sectional view taken along the line 2—2 of Figure 1.

Figure 3 is a sectional end view taken along the line 3—3 of Figure 2.

Figure 4 is an end view of the left-hand end of Figure 2 with a fragment broken away.

Figure 5 is a longitudinal sectional detail view of an externally threaded hollow tubular shaft.

Figure 6 is an end view of the right-hand end of Figure 5.

Figure 7 is a sectional end view taken along the line 7—7 of Figure 5.

Figure 8 is an end view of the left-hand end of Figure 5.

Figure 9 is a sectional top plan view of Figure 5, showing parts of the lock in an open position.

Figure 10 is a sectional end view taken along the line 10—10 of Figure 9.

Figure 11 is a view similar to Figure 9, showing parts of the lock in a locked position.

Figure 12 is a reduced front view of the lock and its supporting plate.

Referring more particularly to the drawings:

With particular reference to Figures 1 and 2, reference numeral 1 indicates a cylindrical housing closed at both of its ends by closure caps 2 and 3 secured in any approved manner as at 4 to the housing. The caps are formed with aligned openings 5 and 6 to provide bearings for

2

an externally threaded hollow tubular shaft 7. The left-hand end of the threaded shaft 7 is freely rotatable within a cap 8, which is rotatably mounted in bearing 5. The opposite end of the shaft 7 is rotatably mounted in the bearing 6 and is provided with an integral flange 9 abutting the inside surface of the supporting plate 3. To the extended portion of the shaft beyond the bearing 6, I secure by spot welding, or the like, a disc 10 to maintain the shaft 7 in a proper operating position within the housing. The right-hand end of the shaft 7 is closed by an insert 11 formed integral with a closure plate 11A which is notched inwardly as at 12 (see Figure 6) for a purpose to be hereinafter described. Mounted concentrically of and surrounding cap 8 is a disc 13 which is formed with a right-angular arm generally indicated at 14, and which extends lengthwise of the interior of the housing as shown. Formed integral with, or secured to, the cap 8 is a flange 14' which maintains the cap within the housing and also maintains said disc 13 and arm 14 in proper position. Spaced inwardly from both ends of the shaft 7 are two spaced apart discs 15 and 16 which are formed with aligned openings through which the shaft 7 is free to rotate. Each disc is formed with diametrically opposed radially extending ears 17 which are slidable in longitudinal slots 18 formed lengthwise of the housing preventing rotation of the disc but allowing them to be moved toward or away from each other within the housing. Between the disc 15 and the flange 14' is a coil spring 19 whose one end bears against the flange 14' and whose opposite end bears against the disc 15. A companion coil spring 20 surrounds the opposite portion of the shaft 7. One end of this spring bears against the disc 16, and its opposite end bears against the inside surface of the closure cap 3. Operatively mounted on the shaft 7 is a traveler nut in the form of one or more coils of wire 21 whose ends terminate in a lug 22 movable between the discs 15 and 16 upon rotation of the shaft 7 through the medium of a crank handle 23 secured to the rotatable disc 10. The angular arm 14 extends inwardly from the disc 13 and rests upon, or is movable along, a track 24 formed within a plate 25 of arcuate form in cross section.

The plate 25 is engaged with the discs 15 and 16 by resting within cut out portions 26 and 27, respectively, in the discs whereby the discs are free to move toward and away from each other with respect to the plate. On the inside marginal edge of the track portion of the plate 25, I form

two depending lugs 28 and 29. On the underside of the arm 14, I form a depending lug 28A at right angles to the lugs 28 and 29. The shaft 7 is provided with two spaced apart outwardly extending studs 30 and 30A to form limit stops for the movement of the nut 21 along the shaft. On one side of the shaft 7 I provide a stop-plate 31 formed with a right-angular wing 32 and reduced at its ends as at 33 for swingable or rockable mounting in notches 34 formed in the discs 15 and 16. A companion stop-plate 31A, having a wing 32A and reduced end portions 33A is likewise mounted in notches 34A formed in the opposite side of the discs 15 and 16.

The outer end of the hollow cap 8 is formed with an abutment in the form of two inwardly turned diametrically opposed fingers 37 and 38 and also a horizontal projection 39. Secured within the left-hand end of the hollow tubular threaded shaft 7 by means of a set-screw 39A is a cylindrical spring housing 40 which is bifurcated for the major portion of its length as at 41 to form a passageway for one of two pins 42 which secure a pair of arms 43 and 44 of a frame 44' together in spaced relation to each other. The cylinder 43 is also slotted longitudinally as at 45 to slidably engage both arms 43 and 44 of the frame. By this arrangement, the frame may be forced outwardly to the position shown in Figure 11 and returned by the spring 46A to the position shown in Figures 5 and 9. The arms are made of a single bar of metal folded back on itself as shown in Figure 5. The top arm 43 is formed with an enlarged horizontal portion 46 of rectangular shape in plan view, and slidable in slots 46A in the corresponding end of the shaft 7.

Pivots attached between the frame arms 43 and 44 is a plurality of keys 47, whose forward ends are formed into identical projections 48 and whose rear ends are tapered downwardly and forwardly as at 49. The bottom edges of the keys are formed with irregular edges 50. In order to force the frame and its horizontal portion to the left as shown in Figures 5, 9, and 11, it is necessary that all of said keys be moved into horizontal alignment with each other so that projections 48 may enter the bifurcation 41 in the spring housing 40, then, upon further advancement, force said horizontal portion 46 to its limit of outward movement. The limit being established by contact of shoulders 51, formed on the keys, coming in contact with the inner end of spring housing 40. To accomplish said alignment of the keys 47 I provide a key in the form of a bar 52 having formed on its top surface a transverse notch 53, and insertable through the notch 12 formed in the cap 11.

The insert 11 in the end of the shaft 7 is channeled as at 54 for a portion of its length and reduced in diameter as at 55 for the remainder of its length. Both sides of this reduced portion are undercut as at 55A to slidably engage the opposite ends of the top and bottom arms 42 and 43 of the frame 44'. One side of the reduced portion 55 is formed with a cavity 56 into which one end 57 of one leg of a spring grip 58 is anchored. The spring extends across through the insert 11, and its opposite leg is extended forwardly as at 59, and is adapted to spring into engagement with a cut-out portion 60 along one edge of the leg 43 of the frame and into abutment with the shoulder 61 at the inner end of the cut-out portion to resist the action of the spring 46A within the spring housing 40.

and to prevent the frame from being moved to the right as viewed in Figure 11.

As best illustrated in Figure 12, the combination closure cap and supporting plate 3 of the lock housing may be of square or round formation and formed with notches 62 and ridges 63 to provide spaced-apart finger-contacting points on its edges and front surface so that an operator may by the sense of touch, count and determine the number of rotations of the screw shaft 7 through the medium of the handle 23, necessary to move the traveler nut along the shaft in either direction to predetermined positions to actuate the lock.

The operation of the lock is as follows: The nut 21 and its lug 22 are limited in their movement lengthwise of the shaft 7 in either direction by the limit-stops 30 and 30A. In other words rotation of the threaded shaft 7 in a counter-clockwise direction will move the nut toward and finally against the limit-stop 30 and clockwise rotation of the shaft will of course move the nut toward and against the limit-stop 30A, for the reason that rotation of the nut with the shaft is being resisted or prevented by contact of the lug 22 with either one of the wings 32—32A of the stop-plates 31—31A, respectively, when in their positions shown in Figures 1 and 2. It will be noted that the length of each of said wings is less than the distance between the limit-stop pins 30 and 30A so that a passageway C is provided between one end of the wing 32 and the limit-stop 30 and also as at D between the opposite end of the wing 32A and the limit-stop 30A. The nut when bearing against the limit-stop 30 will rotate with the shaft, pass through the passageway C and will also pass by the plate 31A and its wing 32A for the reason that said plate and wing will rock inwardly and outwardly respectively about the hinge line established by the plate-extensions 33A being cradled in notches 27 formed in the discs 15 and 16. However, when the shaft and nut are rotated together in a clockwise direction and the lug strikes against the wing 32A further rotation of the nut in that direction will be resisted and prevented because of the rocking of the plate and its wing in an opposite direction whereupon the plate 31A will bear against the wall of the housing 1. Rotation of the nut being thus blocked will cause it to move to the right as viewed in Figures 1 and 2 until the lug 22 clears the right-hand end of the wing 32A and enters the passageway D where it is again free to rotate with the shaft 7. Thus it may be said that a neutral zone of operation exists between the stop pins 30—30A.

The operator will know the exact number of rotations of the shaft in either a clockwise or counter-clockwise direction required to move the nut (now sliding along either of the wings 31 or 31A) to a location where the lug 22 will contact either of the lugs 29 or 28 respectively to stop the rotation of the nut with the shaft. Then upon further rotation of the shaft in a clockwise direction the lug 22 will abut the lug 29A on the end of the arm 14 and will pull the disc 13 and the cap 8 inwardly through the medium of the flange 14' against the resistance of the spring 13. This inward movement of the cap 8 will position its abutments 37—38 in the path of rotary movement of the projection 46 on the outer end of the frame 44'. When the projection 46 and the cap 8 are thus interlocked, further rotation of the shaft 7 in either direction will be imparted to the

cap 8 and its projection 39 for operating any approved type of locking mechanism (not shown) to which my lock is applied and which does not constitute a part of this invention.

Upon rotation of the shaft in a counter-clockwise direction the nut and lug will move to the left as viewed in Figure 2 and thereby restore the cap 8 and its related parts to their extended positions as shown in full lines until the lug reaches the passageway C where it is again allowed uninterrupted rotation, as aforesaid. Removal of the key 52 will allow the frame 44, projection 46 and keys 47 to move to the right by the action of the spring 48A to resume their positions shown in Figure 9.

While I have shown a particular form of embodiment of my invention, I am aware that many minor changes therein will readily suggest themselves to others skilled in the art without departing from the spirit and scope of the invention. Having thus described my invention, what I claim as new and desire to protect by Letters Patent is:

I claim:

1. A lock of the class described comprising in combination, a housing closed at both of its ends, an externally threaded hollow shaft rotatably mounted within said housing, a stop-plate swingably mounted within the housing on each side of said shaft, a traveler nut operatively mounted on said shaft and movable therealong upon rotation of the shaft and when in contact with either of said stop-plates, a cylindrical cap slidably extending through one end of said housing and surrounding one end of said shaft, an arm attached at one of its ends to said cap and terminating at its opposite end in a lug arranged in the path of movement of the traveler nut at predetermined times whereby said cap will be drawn inwardly with respect to the housing upon advancement of the nut along the threads of said shaft, a key-actuated frame slidably mounted within said hollow shaft and adapted to be extended outwardly from one end thereof for engagement with and rotation with said cap when said cap is in said inwardly drawn position.

2. A lock of the class described comprising in combination a housing closed at both of its ends by closure plates, an externally threaded hollow shaft rotatably mounted within said housing, a pair of slidably mounted but non-rotatable spaced-apart discs disposed within the housing and surrounding said shaft, resilient means disposed between each of said discs and its respective end of said housing, a stop-plate disposed on each side of said shaft and swingably engaged with said discs, each of said stop-plates having a right-angular wing extending inwardly toward

said shaft, a traveler nut operatively mounted on said shaft and movable therealong upon rotation of the shaft and when in contact with either of the wings of said stop-plates, a cylindrical cap 5 slidably extending through one of said closure plates and surrounding one end of said shaft, a flange formed on said cap on the interior of said housing, a disc surrounding the cap and disposed between said flange and its respective end of said housing, an arm formed integral with said disc and extending into the housing in the direction of the length thereof, the inner end of said arm terminating in a lug arranged in the path of movement of the traveler nut at predetermined times whereby said cap will be drawn inwardly with respect to the housing upon advancement of the nut along the threads of said shaft, a key-actuated frame slidably mounted within said hollow shaft and adapted to be extended outwardly from one end thereof for engagement with and rotation with said cap when said cap is in said inwardly drawn position.

3. A lock of the class described comprising in combination a housing closed at both of its ends by closure-plates, an externally threaded shaft rotatably mounted within said housing, a traveler nut operatively mounted on said shaft, abutment means within the housing for selectively holding the traveler nut against rotation with the shaft and to cause its advancement along the shaft during rotation of the shaft, a cylindrical cap slidably extending through one of said closure-plates and surrounding one end of said shaft, an arm attached at one of its ends to said cap and terminating at its opposite end in a lug arranged in the path of movement of the traveler nut at predetermined times whereby said cap will be drawn inwardly with respect to the housing upon advancement of the nut along the threads of said shaft, a key-actuated frame slidably mounted within said hollow shaft and adapted to be extended outwardly from one end thereof for engagement with and rotation with said cap when said cap is in said inwardly drawn position, a handle secured to the opposite end of said shaft and rotatable therewith adjacent the other of said closure-plates, and the edge of said last mentioned closure-plate being provided with spaced-apart finger-contacting elements whereby an operator may determine by the sense of touch the number of revolutions applied to said handle and shaft in either direction.
